UNITED STATES PATENT OFFICE.

MARY L. MINNS, OF NEW YORK, N. Y.

PUZZLE.

1,115,856.

Specification of Letters Patent.

Patented Nov. 3, 1914.

Application filed August 27, 1914. Serial No. 858,866.

To all whom it may concern:

Be it known that I, MARY L. MINNS, a citizen of the United States, and a resident of New York, borough of Brooklyn, county 5 of Kings, and State of New York, have invented certain new and useful Improvements in Puzzles, of which the following is a full, clear, and exact description.

This invention relates more particularly 10 to a war puzzle having reference to the countries involved in the present European war.

One of the principal objects of the invention is to provide an interesting puzzle 15 in which the countries allied with each other in the present European war as well as those opposed to them are each represented by a moving element, in this instance a ball, and these balls compelled to pass by abutments or obstructions and in such a way 20 to a certain point or place that they will indicate so far as the working of the puzzle is concerned which countries at war are or will be victorious. The puzzle may also 25 include one or more neutral countries or countries which are likely to be involved in war and which may be made, in the working out of the puzzle, to combine with one or the other of the opposed groups or 30 allied countries.

A further object of the invention is to provide a simple puzzle which is inexpensive to manufacture and which may be worked out in different interesting ways 35 according to the manipulation and desires of the one using the puzzle.

With these and other objects in view, the invention will be hereinafter more particularly described with reference to the accompanying drawings, which form a part of 40 this specification, and will then be pointed out in the claims at the end of the description.

In the drawings, Figure 1 is a plan view 45 of one form of device embodying my invention. Fig. 2 is a vertical section taken on the line II—II of Fig. 1; and Fig. 3 is a transverse section of a slightly modified form of device.

The device comprises a body 10 and a 50 cover 11, the latter being hinged, as at 12, in any suitable way to the body 10 so that it may be folded over upon the said body when not in use. The body as well as the 55 lid or cover may be stamped from tin or may be made from any other suitable ma-

terial and in such a way that the same is inexpensive to manufacture. The bottom 13 of the body 10 has a flat raceway 14 formed therein of substantially annular 60 form and from which radiate grooves or channels 15. These channels 15 may be of any suitable number. As shown, there are eight channels forming radial raceways each having its outer end closed, and opposed to 65 said channels 15 are obstructions or abutments 16 which separate the raceway 14 from an inner substantially flat space, part or pocket 18. The obstructions 16 may represent forts and said obstructions are separated sufficient distances from each other to provide short channels 19 which communicate with the raceway 14 and the inner space 18. The obstructions 16 are of less 70 number than the channels 15 and therefore 75 place most of the short channels 19 out of alinement with the channels 15.

Each country at war is represented by a movable element, in this case a ball. The puzzle is intended primarily for use in connection with the countries at war in Europe and only the principal countries are here represented, though it will be understood that the number of countries represented as well as the general form of the obstructions 80 and channels may be changed at will. As shown, England, France and Russia are represented by red balls 20; Germany and Austria are each represented by a white ball 21, and Italy by a green ball 22, it being the purpose of the puzzle to have the balls variously arranged in the channels 15 or raceway 14, so that those allied with each other should be all made to occupy the space 18 which is intended to represent 90 the place for the victorious forces and is indicated by the word "Victory."

In carrying out one plan of the invention, if one red ball should enter the space 18 then the other red balls should follow. If on the 100 other hand the white ball should first enter the space indicated by the word "Victory" the other white ball should follow and also the green ball representing Italy because of the treaty of alliance with Germany and 105 Austria, or if Italy is allied with England, France and Russia, then it should follow the red balls into the said space. If Italy is neutral it may be made to follow either the white balls or the red balls into the space 18 110 indicated by the word "Victory", it being understood that the arrangement may be

changed to meet the wishes of the one using the puzzle.

It will be readily seen that considerable variations and scope can be given to the puzzle by the addition of different countries represented by a ball and their relation to the other countries, the main purpose of the puzzle being to get all of such countries properly allied with each other in their regular order into the space 18 without having any of the other balls representing the opposing countries enter said space. The difficulty of manipulating the puzzle will depend largely upon the character of the channels, the raceways and the obstructions 16 which may indicate forts, as well as the number of countries represented and their general arrangement with respect to each other.

In Fig. 3, the construction of the puzzle is the same as that shown in Figs. 1 and 2 except that instead of the body 10 having simply the base 13 with the marginal walls about the same and open at the upper surface thereof, said body 10 may be closed on the upper surface by means of a glass plate 23 which may be held to the body 10 by means of a paper or other strip 24 or in any other desired way. The purpose of the plate 23 is to prevent access to the interior of the body 10 by the user of the puzzle.

In the lid of the box 11 may be stamped, printed, lithographed, or otherwise arranged, the name of the puzzle as well as the rules so as to indicate to the user the character and way to operate the puzzle in the manner shown. It will be understood that if desired the lid or cover 11 may be dispensed with and simply the body portion with or without the cover plate 23 employed.

Having thus described my invention, I claim as new and desire to secure by Letters Patent:

1. A device of the character described, comprising a body having its bottom formed with an annular raceway and radiating channels extending outwardly therefrom and with spaced annularly arranged obstructions differing in number from those of the radiating channels and forming an inner space within said obstructions which communicates with the annular raceway and with said channels, and a plurality of elements representing different countries adapted to pass from the radial channels and annular raceway in certain order to the space within said obstructions.

2. A device of the character described, comprising a body having a raceway and channels extending outwardly therefrom

and having spaced obstructions differing in number from those of the outwardly extending channels, said abutments forming an inner space within the same which communicates with the raceway and with said channels, and a plurality of balls representing different countries adapted to pass from the channels and raceway to the space within said obstructions.

3. A device of the character described, comprising a body having its bottom formed with an annular raceway and radiating channels extending outwardly therefrom and with spaced obstructions forming an inner space, said channels having their outer ends closed and a plurality of balls adapted to pass from the radial channels and annular raceway to the space within said obstructions.

4. A device of the character described, comprising a body having its bottom formed with a flat annular raceway having radiating channels extending outwardly therefrom and with spaced annularly arranged obstructions forming an inner flat space which communicates with the annular space and with said channels, said channels having their outer ends closed and a plurality of elements representing different countries adapted to pass from the radial channels and annular raceway in certain order to the space within said obstructions.

5. A device of the character described, comprising a rectangular body having its bottom formed with a raceway having channels extending outwardly therefrom and with spaced obstructions differing in number from those of the channels and forming a central space within said obstructions adapted to communicate with the raceway and with said channels, and a plurality of balls adapted to pass from the channels and annular raceway in certain order to the space within said obstructions.

6. A device of the character described, comprising a body having a bottom with marginal walls and a lid adapted to form a closure for said body, said bottom having an annular raceway and radiating channels, an inner space, and irregularly spaced obstructions, and elements representing different countries adapted to be arranged in certain order within the space.

This specification signed and witnessed this twenty sixth day of August A. D. 1914.
